CHRISTMAS TREE BASE SUPPORT

Edmund D. Jackson, Central City, Nebr.

Application April 4, 1956, Serial No. 40,901

Term of patent 14 years

(Cl. D35—3)

Fig. 1.

Fig. 2.

Fig. 3.

Fig. 4.

Fig. 5.

Figure 1 is a bottom plan view of a Christmas tree base support showing my new design.

Figure 2 is an end elevational view thereof;

Figure 3 is a side elevational view of Figure 1, the other side being substantially the same;

Figure 4 is an end elevational view showing the opposite end of Figure 2; and

Figure 5 is a top plan view of Figure 1.

I claim:

The ornamental design for a Christmas tree base support, as shown and described.
